[57] CLAIM

I claim the ornamental design for a horse head swing saddle, as shown and described.

DESCRIPTION

FIG. 1 is a front perspective view of a horse head swing saddle embodying the present invention.

FIG. 2 is a right side view of a swing having the horse head swing saddle of FIG. 1. and;

FIG. 3 is a top view of the horse head swing saddle of FIG. 1.

The front and rear end of the article not shown in the drawing or described in the specification form(s) no part of the claimed design.

The broken line showing of the handles, footholds and end panels are for illustrative purposes only and form no part of the claim design.
